CLAIM

The ornamental design for a toy tractor and trailer, as shown and described.

DESCRIPTION

FIG. 1 is a perspective view of a farmer tracker and trailer showing my new design;

FIG. 2 is a front view thereof;

FIG. 3 is a right side view thereof, the left side view being a mirror image with the exception of the exhaust mounted on the front right-hand side of the tractor hood;

FIG. 4 is a top view thereof;

FIG. 5 is a bottom view thereof; and,

FIG. 6 is a back view thereof.
